(57) **CLAIM**

The ornamental design for a drain rack, as shown and described.

DESCRIPTION

FIG. 1 is a top, front and right-side perspective view of the drain rack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is bottom, rear and left-side perspective view thereof;

FIG. 9 is an enlarged view, of circled portion 9, of FIG. 2, thereof; and,

FIG. 10 is an enlarged view, of circled portion 10, of FIG. 8, thereof.

The broken lines shown in the drawings illustrate portions of the drain rack and environment that form no part of the claimed design.

The dot-dash broken lines depict the boundaries of the FIGS. 2, 8, 9 and 10 enlargement that forms no part of the claimed design.

1 Claim, 10 Drawing Sheets
